(57) **CLAIM**

The ornamental design for a travel toothbrush with dental floss, as shown and described.

DESCRIPTION

FIG. 1 is an upper left front perspective view of my design in an extended position for a travel toothbrush with dental floss;

FIG. 2 is a rear elevation view thereof;

FIG. 3 is a lower right bottom perspective view thereof;

FIG. 4 is a bottom view thereof;

FIG. 5 is a view corresponding with FIG. 3 showing my design in a folded position and with a length of dental floss exposed;

FIG. 6 is a bottom view corresponding with FIG. 5;

FIG. 7 is a rear elevational view showing my design in a folded position;

FIG. 8 is an upper left front perspective view of my design in a partly folded position; and,

FIG. 9 is a front elevation view of my design in a partly folded position.

The dental floss is shown broken away to indicate an unspecified length.
